UNITED STATES PATENT OFFICE.

GEORGE W. ROEMER AND CHARLES PRIESTER, OF CHICAGO, ILLINOIS, ASSIGNEES OF
ONE-THIRD TO PETER SIPCHEN, OF CHICAGO, ILLINOIS.

RAIL-FASTENING.

1,078,555.

Specification of Letters Patent.

Patented Nov. 11, 1913.

Application filed October 7, 1912. Serial No. 724,330.

To all whom it may concern:

Be it known that we, GEORGE W. ROEMER and CHARLES PRIESTER, citizens of the United States, and residents of the city of Chicago, county of Cook, and State of Illinois, have invented certain new and useful Improvements in Rail-Fastenings, of which the following is a specification.

The invention relates to improvements in rail fastenings and has for its object the provision of a device of this character of simple construction and efficient in operation, the present application being an improvement over the construction disclosed in the prior patent to said George W. Roemer, granted September 3, 1912, No. 1,037,540, for rail supports.

The invention consists in the combinations and arrangements of parts hereinafter described and claimed.

The invention will be best understood by reference to the accompanying drawings forming a part of the specification, and in which,

25 Figure 1 is a section taken through a rail and rail tie showing a fastener embodying our invention, Fig. 2 is a top plan view corresponding to Fig. 1, Fig. 3 is a section taken on line $\alpha-\alpha$ of Fig. 1, Fig. 4 is a section through a rail and rail tie on line $y-y$ of Fig. 5 showing a modified form of fastener, and Fig. 5 is a top plan view corresponding to Fig. 4.

The form of construction illustrated in 35 Figs. 1, 2 and 3 comprises a suitable rail tie 1 formed of cast steel and having a recess 2 formed therein, said recess being substantially U-shaped in horizontal section as indicated in Fig. 2. A perforated fastening block 3 is 40 fitted within recess 2 and provided with an integral upwardly extending fastening member 4 at each side each provided with a nose or projection 5 adapted to take over the flange 6 of rail 7 resting upon tie 1. A substantial recess 8 is formed in tie 1 below recess 2 and is connected with recess 2 by 45 means of an oblong passage 9 as shown. A bolt 10 is provided with an oblong head 11 adapted to pass through recess 9 and turn in recess 8. One side of recess 8 is provided with a stop shoulder 12 which is adapted to limit the rotation of head 11 therein. By 50 this arrangement it will be observed that the head 11 and bolt 10 may be inserted through recess 9 and turned until one side

strikes shoulder 12 whereupon said head will be locked securely in recess 8 to prevent vertical movement. The fastening block 3 is then placed over the shank of bolt 10 and a nut placed upon the threaded end of said bolt. In fastening the rail in position, a flange thereof is placed under the noses 5 of members 4 and the fastening block is drawn to position by means of the nut on bolt 10. It will be observed that the arrangement is 60 such that the nut on bolt 10 is contained in recess 2 so as to be concealed from view and protected from injury. The construction set forth is strong and durable and constitutes but few parts, the principal improvement on the prior application of the said George W. Roemer consisting in employing a fewer number of parts.

In the modified form of construction illustrated in Figs. 4 and 5, the fastening block 75 3' is provided with but a single fastening member 4' positioned centrally thereon and recess 2' is modified to correspond. Otherwise the construction and operation is the same as that previously described.

While we have illustrated and described the preferred form of construction for carrying our invention into effect, this is capable of variation and modification without departing from the spirit of the invention. We, therefore, do not wish to be limited to the precise details as set forth, but desire to avail ourselves of such variations and modifications as come within the scope 80 of the appended claims.

Having described our invention, what we claim as new and desire to secure by Letters Patent is:

1. The combination with a rail tie having upper and lower communicating recesses 95 therein, of a perforated block seated in said upper recess and provided at each side with an integral upwardly projecting fastening member formed integral therewith adapted for engagement with a rail flange; a bolt 100 passing through said block perforation and having its head anchored in said lower recess; a shoulder formed on said tie adapted for limiting the rotation of said head in the said recess, substantially as described.

2. The combination with a rail tie having upper and lower communicating recesses, of a perforated block seated in said upper recess; and having an integral upwardly projecting fastening member formed thereon 110

and adapted for engagement over said rail flange; a bolt arranged for location in said block perforation and having its lower portion anchored in said lower recess; and a shoulder formed on said tie projecting into said lower recess, adapted for limiting the rotation of said bolt in said block, substantially as described.

3. The combination with a rail tie having 10 a recess therein, of a perforated block fitting into said recess and provided at each side with an upwardly projecting fastening member formed integrally therewith and adapted to engage over a rail flange; a bolt

anchored in said recess below said block and 15 passing through said block; and a nut on said bolt engaging the top of said block and contained within said recess, substantially as described.

In testimony whereof we have signed our 20 names to this specification in the presence of two subscribing witnesses.

GEORGE W. ROEMER.
CHARLES PRIESTER.
